CLAIM

An ornamental design for a folding table, as shown and described.

DESCRIPTION

FIG. 1 is a front perspective view of our folding table from the upper right side;

FIG. 2 is a top plan view of our folding table;

FIG. 3 is a front elevational view of our folding table;

FIG. 4 is a left side elevational view of our folding table;

FIG. 5 is a bottom plan view of our folding table;

FIG. 6 is a right side elevational view of our folding table;

FIG. 7 is a back elevational view of our folding table;

FIG. 8 is a front perspective view showing the fully unfolded table-ready for use;

FIG. 9 is a front perspective view showing the table with legs folded together; and,

FIG. 10 is a front perspective view showing the fully unfolded table-ready to carry or store.
